(57) **CLAIM**

The ornamental design for a food carrier, as shown.

DESCRIPTION

FIG. 1 is a front perspective view of a food carrier showing my new design;

FIG. 2 is a left side elevational view thereof, the right side elevational view being a mirror thereof;

FIG. 3 is a top plan view thereof;

FIG. 4 is a left end view thereof, the right end view being a mirror image; and,

FIG. 5 is a bottom plan view thereof.

Each of the views include in broken lines the food packaging which the carrier is designed to transport, such broken lines being used to show a visible environmental structure which is not part of the invention.
